(57) **CLAIM**

The ornamental design for an architectural panel, as shown and described.

DESCRIPTION

FIG. 1 is a bottom, front, right perspective view of an architectural panel according to a first embodiment of our new design;

FIG. 2 is a top, front, right perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a bottom plan view thereof;

FIG. 8 is a top plan view thereof;

FIG. 9 is a bottom, front, right perspective view of an architectural panel according to a second embodiment of our new design;

FIG. 10 is a top, front, right perspective view thereof;

FIG. 11 is a front elevation view thereof;

FIG. 12 is a right side elevation view thereof;

FIG. 13 is a rear elevation view thereof;

FIG. 14 is a left side elevation view thereof;

FIG. 15 is a bottom plan view thereof; and,

FIG. 16 is a top plan view thereof.

The figures show a symbolic break in FIGS. 9-16. The break lines, as well as any portion of the article between the break lines, form no part of the claimed design. The broken lines illustrating portions of the architectural panel form no part of the claimed design. The dot-dash broken lines define the bounds of the claimed design and form no part thereof.
